(57) **CLAIM**

The ornamental design for a vehicle rooftop tent carrier, as shown and described.

DESCRIPTION

FIG. 1 is a side elevational view of an embodiment of the vehicle rooftop tent carrier shown on a vehicle.

FIG. 2 is a top perspective view of the vehicle rooftop tent carrier.

FIG. 3 is a top plan view of the vehicle rooftop tent carrier.

FIG. 4 is a bottom plan view of the vehicle rooftop tent carrier.

FIG. 5 is a left side elevational view of the vehicle rooftop tent carrier.

FIG. 6 is a right side elevational view of the vehicle rooftop tent carrier.

FIG. 7 is a rear elevational view of the vehicle rooftop tent carrier.

FIG. 8 is a front elevational view of the vehicle rooftop tent carrier.

FIG. 9 is top plan view of another embodiment the vehicle rooftop tent carrier, the front elevational view, the rear elevation view, the left side elevational view, the right side elevational view and the bottom plan view being the same as shown in FIGS. 4-8.

FIG. 10 is top plan view of a further embodiment the vehicle rooftop tent carrier, the front elevational view, the rear elevation view, the left side elevational view, the right side elevational view and the bottom plan view being the same as shown in FIGS. 4-8; and,

FIG. 11 is top plan view of a further embodiment the vehicle rooftop tent carrier, the front elevational view, the rear elevation view, the left side elevational view, the right side elevational view and the bottom plan view being the same as shown in FIGS. 4-8.
